No. 15,710.

PATENTED SEPT. 9, 1856.

R. A. SMITH.
STREET SWEEPING MACHINE.

UNITED STATES PATENT OFFICE.

ROBT. A. SMITH, OF BROOKLYN, NEW YORK.

MACHINE FOR SWEEPING STREETS.

Specification of Letters Patent No. 15,710, dated September 9, 1856.

To all whom it may concern:

Be it known that I, ROBERT A. SMITH, of Brooklyn, in the county of Kings and State of New York, have invented a new and 5 useful Improvement in Street-Sweeping Machines; and I do hereby declare that the following is a full, clear, and exact description of the construction and operation of the same, reference being had to the annexed drawing, forming part of this specification, in which—

Figure 1 is a top view of the machine. Fig. 2 is a side elevation of the same. Fig. 3 is a horizontal section on line $y-y$. Fig. 4 15 is a vertical section on line $z-z$. Fig. 5 is a section on $x-x$ taken perpendicular to the side of the machine. Fig. 6 is a view showing manner of fastening brush stock upon end castings.

20 Similar characters of reference in the several figures denote the same part of the machine.

The nature of my invention consists in the construction of street sweeping machines 25 with the main broom cylinder hung directly under the axle of the traveling wheels; and with an elevator hung upon the shaft of the moving pinion, and traveling by means of rollers directly upon the street surface. 30 Also in constructing the machine with a gutter brush having its brooms set spirally to carry the sweepings of the gutter into the track of the main broom. This construction of machine with the adjustments connected 35 therewith, hereinafter to be described, constitute my invention, which will readily be understood from the following description and reference to the drawing, in which the several parts are thus represented.

40 A frame, made light, and mounted on three wheels, so as readily to be attached to an ordinary cart; B broom cylinder, hung under axle a of traveling wheels by chains $c-c$, and rotated by endless chains b . The 45 boxes d of the brush axle c move in curved guides f described around the axis of the pulley shaft g , so as in all positions of the broom cylinder to preserve the tightness of the driving chain b . This cylinder is raised 50 and lowered by means of the wheel h and worm or screw i . C elevator frame, hung in main frame on shaft j , and provided with wheels or rollers k at bottom. It is adjusted in inclination by the brace l and pin, 55 or by a ratchet lever. Within this frame is the elevator, consisting of apron m and a

series of buckets n , and moved by chain o passing over pulleys p and q . Along the sides of the conveyer run the chains $r-r'$, serving as sides to the buckets, and as movers of the elevator. D gutter brush, with brooms set spirally, suspended forward of main cylinder broom, the opposite end of its shaft s being held by box y and movable in guides x by screw t (as shown in Fig. 4), 60 for the adjustment of the brush to the inclination of the gutter. This brush is rotated by chain a' passing over a pulley on shaft of main cylinder and pulley b' on shaft s . E casing on under side of elevator 65 frame for catching the dirt thrown over the sides of the elevator by the brooms and by reason of its inward inclination depositing it in the track of the brush cylinder, and thus preventing the ridges of dirt left by 70 other machines.

The broom cylinders are made up of a shaft upon which are cast heads with flanges, into which the brush blocks are fitted, while bolts fasten the said brush 75 blocks upon the heads, this insures the firm construction of the brush and at the same time enables a single block to be removed at pleasure for repair or replacement.

The operation of the machine is as follows: The machine is attached to the rear of an ordinary cart, and drawn forward. The rotation of the large spur wheel G , gives motion to shaft g through pinion H , producing movement of chain b and rotating main brush cylinder. This sweeps the dirt directly upon the endless conveyer, which is moved upward by the meshing of pinion I with pinion H , giving motion to shaft f . The dirt thus carried up falls into 85 the cart in front. Meantime the gutter brush, adjusted to the proper inclination, revolves by chain connection a' with the main brush, and by reason of the spiral arrangement of its brooms carries the dirt 90 from the gutter into the path of the main cylinder brush. The dirt thrown over the sides of the conveyer, by the brooms falls into the inward inclined case and is thus deposited in the path of the brush as above 95 described. The method of adjusting the gutter brush by means of the box y , screw t and guides x , prevents all motion to the end of the shaft s , except that of rotation since the screw t will not prevent the box to move 100 in the guides and the guides will prevent its lateral movement. For this reason the ar-

arrangement specified presents an obvious advantage over any other mode of suspending the end of shaft *s*. When the brooms wear, the cylinder is adjusted by the turning of screw *i* as above described.

The hanging of the main cylinder under the axle *a* enables the brooms to conform to the inequalities of surface passed over, a result not attained by the usual mode of hanging the brush in front or behind that axle.

In this machine the main brush cylinder, the elevator and the gutter brush bear an important relation to each other and to the mechanism operating said parts; since the elevator runs on the ground in front of the main brush and is adjustable to conform to said cylinder. And moreover the gutter brush acts with the main cylinder brush in delivering the dirt to the conveyer. The gearing connection is such that the gutter brush is driven from the shaft of the cylinder brush, and the conveyer is driven from the shaft on which its frame is hung motion being communicated to that shaft from the rotation of the shaft giving motion to the main cylinder. Thus the several parts of this machine are rendered mutually dependent on each other, and operate together as a whole. The brush end of the gutter brush shaft is raised and lowered by means of a chain attached to said shaft and

passing over a pulley on shaft *m'*, this shaft being rotated by crank *u'*.

What I claim as new and desire to secure by Letters Patent is—

35

1. Placing the main broom cylinder under the axle of the traveling wheels substantially as, and for the purposes set forth.

2. The curved guides *f* of broom cylinder axle, concentric with the driving pulley, for keeping the driving band tight in all positions of the said cylinder.

40

3. Hanging the conveyer on its driving shaft with its lower extremity resting on wheels running on the surface of the ground, as and for the purposes specified.

45

4. The arrangement of screw, box and guides with the shaft of the gutter brush, for regulating the inclination and preventing the oscillation of the said brush substantially as specified.

50

5. The combination of the cylinder brush, and gutter brush with the elevator, arranged and operating substantially as, and for the purposes specified.

55

In testimony whereof I have hereunto signed my name before two subscribing witnesses.

ROBERT A. SMITH.
